US00D929252S

(12) **United States Design Patent** (10) Patent No.: **US D929,252 S**
(45) Date of Patent: **** Aug. 31, 2021**

(54) **EARRING**

(71) Applicant: **Venus by Maria Tash, Inc.**, New York, NY (US)

(72) Inventor: **Maria Tashjian**, New York, NY (US)

(73) Assignee: **Venus by Maria Tash, Inc.**, New York, NY (US)

(**) Term: **15 Years**

(21) Appl. No.: **29/758,997**

(22) Filed: **Nov. 19, 2020**

Related U.S. Application Data

(63) Continuation of application No. 29/698,112, filed on Jul. 15, 2019, now Pat. No. Des. 902,772.

(51) **LOC (13) Cl.** **11-01**

(57) **CLAIM**

An ornamental design for an earring, as shown and described.

DESCRIPTION

FIG. 1 is a front perspective view of an earring;
FIG. 2 is a front side view of the earring;
FIG. 3 is a back side view of the earring;
FIG. 4 is a right side view of the earring;
FIG. 5 is a left side view of the earring;
FIG. 6 is a bottom side view of the earring; and,
FIG. 7 is a top side view of the earring.
Broken lines shown in drawings illustrate portions of the earring that form no part of claimed design.
